Patented Nov. 11, 1919.

UNITED STATES PATENT OFFICE.

EBENEZER M. BLISS, OF BERKELEY, CALIFORNIA.

WATER-CLOSET-FLUSHING APPARATUS.

1,321,413.

Specification of Letters Patent. Patented Nov. 11, 1919.

Application filed October 18, 1917. Serial No. 197,185.

To all whom it may concern:

Be it known that I, EBENEZER M. BLISS, a citizen of the United States, residing at Berkeley, in the county of Alameda and 5 State of California, have invented new and useful Improvements in Water-Closet-Flushing Apparatus, of which the following is a specification.

This invention relates to an apparatus 10 for flushing water closets, and it has for its object the provision of such an apparatus which is simple and compact in construction so that the same can be produced at comparatively low cost and is not liable to 15 get out of order and can be readily built in or concealed within the wall of a building, and which will efficiently and thoroughly flush a water closet and combine the advantages of both an open water tank 20 and a closed water tank.

In the accompanying drawings:

Figure 1 is a vertical section of a water closet flushing apparatus embodying an approved form of my invention. Fig. 2 is 25 a horizontal section taken on the correspondingly-numbered line in Fig. 1, looking upwardly.

Similar characters of reference refer to like parts in both figures.

30 The main water supply or storage tank 1 of this apparatus may be of any suitable construction, but as shown in the drawings the same preferably comprises a lower cast metal section 2 having an integral bottom 35 and an upper wrought metal section 3 which is connected at its lower end with the upper end of the lower section by means of a screw joint and provided at its upper end with a movable screw cap 4 whereby access 40 may be had to the interior of the tank, when necessary, for inspection, adjustment or repairs. At its lower end this water tank is provided with a water inlet 5 through which water may be supplied to the tank 45 by means of a pipe 6 from a water main or any suitable source.

At a suitable distance above its water inlet the storage tank is provided with a water outlet or passage which is valve-controlled.

50 This water passage and its valve mechanism may be variously constructed but as shown in the drawings, by way of example, the same comprises an externally-threaded collar 7 arranged around a water outlet 8 in 55 the side of the water tank, an externally-threaded bushing 9 having a forwardly-

tapering conical valve seat 10 which is arranged in line with the outlet opening 8 of the water tank, and a nipple or tubular coupling 11 provided at its opposite ends with 60 internal screw threads one of which engages with the external thread of the collar 7 and the other with the external thread of said bushing. Within this passage is arranged a valve 12 which is preferably of 65 forwardly-tapering conical form and adapted to be moved horizontally toward and from the seat 10 of the bushing for the purpose of closing or opening the water outlet 70 passage of the water storage tank. This 70 valve is preferably mounted upon a horizontal valve stem 13, 14 the rear end of which is guided in a bridge or cross piece 15 mounted on the interior of the nipple 11 and preferably formed integrally therewith 75 for economy and convenience of manufacture.

When this valve is open, any water within 80 the storage tank above the outlet opening 8 will flow through the space between the valve and its housing or casing which is formed by the nipple 11 and adjacent parts and when this valve is closed the further escape of water is cut off, but at no time will the level of the water descend 85 below the water outlet opening 8, so that a quantity of water is always present in the lower part of the tank which will operate 90 as a cushion into which the new incoming water from the service pipe will be directed and thus prevent the creation of any bubbling or churning noise which otherwise 95 would be produced by the rushing in of water from the supply pipe into the completely emptied tank.

In the upper part of the storage tank is 100 arranged an air vent or ventilating passage which is valve-controlled and through which air is permitted to pass into the upper part of the storage tank and out of the same during the operation of the apparatus for the purpose of permitting the storage tank to be filled with water to a suitable height and also to permit the water to promptly 105 flow out of this tank. This air passage is so organized that the same also forms part of the casing of the valve mechanism which controls this vent passage and the lower part of this air passage is arranged immediately above the water outlet of the tank 110 while its upper end opens into the upper part of the tank above the normal water 115

line therein. Although this air passage may be variously constructed that shown in the drawings comprises a collar 16 surrounding an opening in the side of the storage tank 5 and provided with an external and internal screw thread, an upright pipe 17 arranged within the storage tank and provided at its lower end with an external screw-threaded elbow 18 which engages with the internal 10 thread of the collar 16, while its upper end is open and arranged within the upper part of the tank and retained in place therein by means of a bracket 19 projecting inwardly from the wall of the tank, an externally screw threaded bushing 20 provided with a forwardly-tapering conical valve seat 21, and a nipple or tubular coupling 22 having its opposite ends provided with internal screw threads one of which 15 engages with the external thread of the collar 16 and the other with the external thread of the bushing 20, as shown in Fig. 1. The valve 23 which controls this air passage is preferably of conical forwardly-tapering 20 form and arranged within the valve casing formed partly by the nipple or coupling tube 22, and is movable horizontally into and out of engagement with the valve seat 21 for the purpose of closing or opening 25 the air passage. The rear end of the stem 24, 24 of this valve is guided in a cross piece or bridge 26 formed integrally with the sleeve or nipple 22 on the interior thereof in the same manner in which this is effected 30 with reference to the water outlet valve previously described. While the water outlet 12 is open the air valve 23 is also open so as to admit air to the top of the storage tank and avoid the formation of a vacuum 35 therein as the water flows out of the water tank through the water outlet passage, thereby permitting the discharge of the water to be effected promptly and quickly and effect a thorough flushing of the closet. 40 Upon closing both the water valve and the air valve, the water delivered by the service pipe 6 into the storage tank will rise in the latter and compress the air which is trapped in the upper part of this tank until the 45 maximum resistance has been reached after which the further inflow of water will cease. It will thus be noted that by means of 50 this construction the water tank is completely closed during the time that the same is being filled with a charge of water and thereby prevents the formation of any objectionable noise, but the instant the air and water valves are opened the water tank, in effect, becomes an open tank so as to permit 55 the quick discharge of water therefrom, thereby combining the advantages both of a closed water tank and an open water tank of the types heretofore known.

The water and air valves are preferably 60 opened simultaneously, or substantially so,

and a variety of means may be provided for accomplishing this purpose, but those which are shown in the drawings are preferred and so mounted that the housing or casing which incloses this valve operating mechanism also serves as a conduit through which the water flows from the storage tank to the water closet and also in a conduit through which the air flows to and from the passage leading to the top of the storage tank. 70 Accordingly, this valve mechanism and the manner of operating and mounting the same is preferably constructed as follows:

27 represents an upright operating chamber which is arranged in front of the water storage tank and which is provided at its lower end with a discharge pipe or passage 28 leading to the water closet while its upper end is closed by a detachable cover 29 and its rear side is provided with a lower water inlet opening 30 having an internal screw thread which receives the front part of the external threaded bushing 9 of the water valve mechanism and an upper internally-threaded opening 31 which receives the front part of the externally-threaded bushing 20 of the air valve mechanism. In the cover 29 is arranged an air inlet opening 32 which preferably receives a vent or ventilating pipe 33 extending above the 95 highest water level in the tank 1 and leading to any suitable place and serving to permit air to enter and leave the operating chamber as the air passes back and forth between this chamber and the water tank 100 through the ventilating passage leading to the top of the storage tank.

34 represents an upright operating shaft or spindle which is journaled on the operating chamber so as to be capable of a horizontal rocking movement, the lower part of this shaft being arranged within the chamber and its upper part above the same and the journaling of this shaft being effected by engaging its lower end with a pivot pin 110 34^a projecting upwardly from the bottom of the operating chamber while the upper part of this shaft turns in an opening or bearing 35 formed in the cover of the operating chamber. At its upper end and externally of the operating chamber, this shaft is provided with a handle or finger piece 36 for turning the same and within this chamber this shaft is provided with a crank which preferably is formed by two screw 120 eyes or bolts 37 secured to the side of the shaft one above the other. To this crank is pivotally secured a yoke 38 which is capable of swinging horizontally in the same plane as the operating shaft, the pivotal connection between this yoke and the crank being preferably effected by providing the inner end of the yoke with upwardly or downwardly projecting pivot pins or trunnions 39 which engage respectively with the 130

eyes of the bolts 37 forming the crank. At its outer end this yoke is provided with an upright slot 40 in which is arranged an equalizer 41 which is operatively connected 5 with the water and air valves. This equalizer is preferably constructed in the form of an upright lever which has its central part arranged in and pivotally connected with the slotted part of the yoke by means of a 10 horizontal pivot pin 42 passing transversely through the yoke and the central part of the equalizing lever. The lower arm of the latter is pivotally connected by means of a pin 43 with the front end of the stem 15 of the water valve and the upper arm of the same is similarly connected by means of a pin 44 with the front end of the stem of the air valve.

Upon turning the operating shaft backwardly, its crank will carry the yoke in the same direction which movement will in turn be transmitted by the equalizing lever to both water and air valves and cause both the water outlet and air passage of the water 20 tank to be opened, so that the charge of water in the latter will be permitted to flow through the operating chamber and the discharge pipe of the latter to the water closet and air will be permitted at the same 25 time to pass from the external atmosphere into the upper part of the storage tank to compensate for the water issuing therefrom and prevent any retarding effect on the outflow of such water. Upon turning the operating shaft forwardly, this movement is 30 transmitted by the crank, yoke and equalizing lever to the valves, so that they are closed and thereby cause the water tank to be again filled with another charge of water 35 preparatory to effecting the next flushing 40 operation.

Inasmuch as both valves move outwardly against their seats, the pressure of the water and the compressed air within the storage 45 tank operates constantly to hold these valves against their seats, thereby reducing to a minimum the liability of leakage and insuring satisfactory operation of this flushing apparatus.

50 In order to permit of easily opening the water valve and insure a prompt and quick discharge of the water from the storage tank to the closet, the water valve and its port or seat are made comparatively large, 55 but the air valve and its seat or port are made comparatively small. As the result of differential in areas of these valves the predominating pressure of the water against the back of the water valve will cause the 60 water valve to be held shut momentarily after the air valve has been opened during the first part of the backward movement of the operating shaft, during which time the equalizing lever rocks on the yoke, but 65 after the initial opening movement of the

air valve has been effected, the lower part of the yoke preferably at the lower corner between the back of the slot and the underside of the yoke, as indicated at 45, forms a stop which engages with the lower arm of 70 the equalizing lever and thereafter pushes the same rearwardly positively together with the upper arm thereof, so that the further backward movement of the operating shaft causes the water valve to be opened 75 with the air valve, thereby permitting the escape of water from the tank at the lower end thereof, while air is entering the upper end of the same. It will be obvious that by means of this equalizing lever both valves 80 are capable of properly engaging their seats and closing their respective passages independently of each other, and they are also simultaneously moved away from these seats for opening these passages fully, although 85 they are operated from the same shaft, thereby materially simplifying the construction of this operating mechanism.

In order to facilitate the setting of these valves when they are originally assembled, 90 and also to permit subsequent correction or adjustment of the same, relatively to each other, or for taking up wear if this at any time should be necessary, one or both of these valves has its stem made in sections which 95 are adjustably connected so as to permit of shortening or lengthening the stem. As shown in the drawings, the stems of both of the water and air valves are provided 100 with adjusting means, but if only one such adjustment is provided the same is preferably associated with the air valve because the same is more readily accessible from the top of the operating chamber after the cover of the latter has been removed. As shown 105 in Fig. 1, the valve-stem of the air valve comprises the two sections 24, 25 which are connected respectively with the air valve and the upper arm of the equalizing lever and a screw sleeve or nipple 46 having a screw 110 connection with the opposing ends of the stem sections 24, 25 of the air valve. As shown, these valve stem sections are provided with right and left hand screw threads which 115 cooperate with corresponding threads in said sleeve, whereby a turning movement of the latter in one direction or the other will cause this valve stem to be shortened or lengthened, but if desired these screw threads may all run in the same direction in which case either one of these stem sections may be screwed into this sleeve or out of the same, for the purpose of shortening or lengthening the stem as a whole. A similar screw sleeve 47 may be employed for connecting the sections 13, 14 of the water valve 120 stem and adjusting the same when assembling the apparatus.

In the absence of any provision to prevent it, the operating shaft after being turned 130

backwardly for opening the water and air valves would immediately be turned forwardly and the water and air valves would close if the backward hand pressure of the operator were removed at this time, thereby stopping the discharge of the water from the tank into the closet before the latter had been properly flushed. In order to prevent the immediate closing of the air and water valves, even though the backward hand pressure of the operator is removed, a water controlled retarding mechanism is provided which is preferably constructed as follows:

15 48 represents a ratchet wheel which is secured to the upper part of the operating shaft. 49 represents a locking or detent dog which is adapted to move into and out of engagement with the teeth of the ratchet wheel. This dog is arranged on the upper arm of a rock lever 50 which is arranged in the front part of the operating chamber and pivoted by means of a horizontal pin 51 to supporting lugs 52 arranged on the inner 20 side of this chamber. On the lower arm of this rock lever is arranged a pressure wing 53 which is arranged in the path of the stream of water as it flows across the lower end of the operating chamber from the inlet 25 thereof to the outlet of the same. 54 represents a spring which normally tends to turn the rock lever in the direction in which the detent dog is disengaged from the ratchet wheel, this spring in its preferred form being secured to the lower end of the rock lever and engaging with the adjacent part of the 30 operating chamber.

When free, the operating shaft constantly tends to turn in a forward direction under 35 the action of a spring 55 which aids the air and water pressure in the storage tank in holding the air and water valves tightly against their seats. In the preferred form this last-mentioned spring is constructed in 40 the form of a coil which surrounds the upper part of the operating shaft and is secured at its upper end in the top of the operating chamber while its lower end is secured to the ratchet wheel, as shown in Fig. 1.

45 50 When both the air and water valves are closed, and no water is flowing through the operating chamber, then the spring 54 turns the rock lever in the direction for disengaging the dog from the ratchet wheel. When 55 however the operating shaft has been turned backwardly, so that the air and water valves are both open, and the water is flowing from the storage tank through the lower part of the operating chamber to the water closet, 60 then the pressure of the stream of water against the wing 53 of the rock lever, causes the latter to be turned in the direction for engaging the detent dog with the ratchet wheel, as indicated in Fig. 1, thereby holding 65 the operating shaft against forward ro-

tation and retaining the valves in their open position notwithstanding that the backward pressure of the hand of the operator has been removed from the handle. The parts remain in this position until the batch 70 of water has been discharged from the storage tank to the closet and no further water pressure is exerted against the wing, at which time the spring 54 turns the rock lever so as to disengage the dog from the ratchet 75 wheel after which the spring 55 turns the operating shaft forwardly and moves both the water and air valves against their seats so as to again seal the storage tank and cause the same to be filled with another charge of 80 water.

In order to cause the mechanism intermediate of the rock shaft and the valves to exert a straight pull upon these valves, this rock shaft is journaled out of line with 85 the center of the operating chamber and sufficiently on one side of the center lines of the valves and their seats, as shown in Fig. 2, so that when the crank of this shaft exerts a forward pull on the valves through 90 the medium of the intermediate connecting mechanism, this pull will be substantially straight relative to the axes in center of these valves and thereby cause the same to bear evenly and uniformly and insure a 95 proper closure of the same, so that no leakage occurs.

My improved water closet flushing device is particularly advantageous owing to the absence of float controlled valves or 100 suction valves, also on account of the simplicity of its construction, the freedom from getting out of order, the ease with which the same can be operated and the effectiveness of its cleaning operation. 105

I claim as my invention:

1. A closet flushing apparatus comprising a water tank permanently closed at its upper end and having a water inlet at its lower end, a water outlet above its lower end and an air passage above said water outlet, said water outlet and air passage being independent of each other, and water and air valves arranged outside of said water tank and controlling said water outlet and 110 air passage.

2. A closet flushing apparatus comprising a water tank permanently closed at the top and having a water inlet at its lower end, a water outlet above its lower end and 120 an air passage having its lower end arranged immediately above said water outlet and its upper end opening into the upper end of said water tank, said water outlet and air passage being independent of 125 each other, and water and air valves arranged outside of said water tank and controlling said water outlet and air passage.

3. A water closet flushing apparatus comprising a water tank having a water inlet 130

at its lower end, a water outlet above its lower end, and an air passage which has its lower end arranged immediately above said water outlet and its upper end opening into the upper part of said tank, water and air valves arranged outside of said tank and controlling said water outlet and air passage, means for operating said valves and a chamber communicating with said water outlet and air passage and having a discharge passage and inclosing said means which operate said valves. 5

4. A water closet flushing apparatus comprising a water tank having a water inlet at its lower end, a water outlet above its lower end, and an air passage which has its lower end arranged immediately above said water outlet and its upper end opening into the upper part of said tank, water and air valves for controlling said water outlet and air passages, and means for operating said valves comprising a rock shaft having a crank, a yoke pivoted on said crank, and an equalizer pivoted on said yoke and connected on opposite sides of its pivots with said valves. 10

5. A water closet flushing apparatus comprising a water tank having a water inlet at its lower end, a water outlet above its lower end, and an air passage which has its lower end arranged immediately above said water outlet and its upper end opening into the upper part of said tank, water and air valves for controlling said water outlet and air passages, and means for operating said valves comprising a rock shaft having a crank, a yoke pivoted on said crank and having a stop, and an equalizer lever pivoted between its ends on said yoke in position to engage its lower arm with said stop and having its opposite arms connected with said valves, respectively. 30

6. A water closet flushing apparatus comprising a water tank having a water inlet at its lower end, a water outlet above its lower end and at the side thereof, and an air passage arranged above said water outlet and at the side of said tank, an operating chamber communicating with said water outlet and air passage and provided below said water outlet with a discharge passage, water and air valves for controlling said water outlet and air passage, an operating shaft arranged in said operating chamber and provided within the same with a crank and externally thereof with a handle and intermediate means operatively connecting said crank with said valves. 50

7. A water closet flushing apparatus comprising a water tank having a water inlet at its lower end, a water outlet above its lower end and at the sides thereof, and an air passage arranged above said water outlet and at the side of said tank, an operating chamber communicating with said water

outlet and air passage and provided below said water outlet with a discharge passage, water and air valves for controlling said water outlet and air passage, an operating shaft arranged in said operating chamber 70 and provided within the same with a crank and externally thereof with a handle, intermediate means operatively connecting said crank with said valves and means for retarding the closure of said valves. 75

8. A water closet flushing apparatus comprising a water tank having a water inlet at its lower end, a water outlet above its lower end, and an air passage arranged above said water outlet, an operating chamber communicating with said water outlet and air passage and provided below said water outlet with a discharge passage, water and air valves for controlling said water outlet and air passage, an operating shaft arranged in said operating chamber 80 and provided within the same with a crank and externally thereof with a handle, intermediate means operatively connecting said crank with said valves and means for retarding the closure of said valves 85 comprising a ratchet wheel secured to said shaft within said chamber, and a dog which is responsive to the pressing of the stream of water flowing through said chamber and engages said ratchet wheel for preventing backward rotation of said shaft. 90

9. A water close flushing apparatus comprising a water tank having a water inlet at its lower end, a water outlet above its lower end, and an air passage arranged above said water outlet, an operating chamber communicating with said water outlet and air passage and provided below said water outlet with a discharge passage, water and air valves for controlling said water outlet and air passage, an operating shaft arranged in said operating chamber and provided within the same with a crank and externally thereof with a handle, intermediate means operatively connecting said crank with said valves and means for retarding the closure of said valves comprising a ratchet wheel secured to said shaft within said chamber, 100 a dog adapted to engage with said ratchet wheel, a rock lever carrying said dog, and a wing arranged on said lever in the path of the water flowing through said chamber. 110

10. A water closet flushing apparatus comprising a water tank having a water inlet at its lower end, a water outlet above its lower end, and an air passage arranged above said water outlet, an operating chamber communicating with said water outlet and air passage and provided below said water outlet with a discharge passage, water and air valves for controlling said water outlet and air passage, an operating shaft arranged in said operating chamber and provided within the same with a crank and externally 115

thereof with a handle, intermediate means operatively connecting said crank with said valves and means for retarding the closure of said valves comprising a ratchet wheel secured to said shaft within said chamber, a dog adapted to engage with said ratchet wheel, a rock lever carrying said dog, a wing arranged on said lever in the path of the water flowing through said chamber and a spring operating constantly to turn said shaft forwardly.

11. A water closet flushing apparatus comprising a water tank having a water inlet at its lower end, a water outlet above its lower end, and an air passage arranged above said water outlet, an operating chamber communicating with said water outlet and air passage and provided below said water outlet with a discharge passage, water and air valves for controlling said water outlet and air passage, an operating shaft arranged in said operating chamber and provided within the same with a crank and externally thereof with a handle, intermediate means operatively connecting said crank with said valves and means for retarding the closure of said valves comprising a ratchet wheel secured to said shaft within said chamber, a dog adapted to engage with said ratchet wheel, a rock lever carrying said dog, a wing arranged on said lever in the path of the water flowing through said chamber, a spring operating constantly to turn said shaft forwardly and a spring operating to turn said rock lever in the direction for disengaging said dog from said ratchet wheel.

12. A water closet flushing apparatus comprising a water tank having a water inlet at its lower end, a water outlet above its lower end and at the side thereof, and an air passage arranged above said water outlet and at the side of said tank, an operating chamber communicating with said water outlet and air passage and provided below said water outlet with a discharge passage, water and air valves for controlling said water outlet and air passage, on operating shaft arranged in said operating chamber and

provided within the same with a crank and externally thereof with a handle, intermediate means operatively connecting said crank with said valves and a vent pipe connected with the upper part of said operating chamber.

13. A water closet flushing apparatus comprising a water tank having a water inlet at its lower end, a water outlet above its lower end, and an air passage arranged above said water outlet, an operating chamber communicating with said water outlet and air passage and provided below said water outlet with a discharge passage, water and air valves for controlling said water outlet and air passages, valve stems on which said valves are mounted, the valve stem of said air valve having two threaded sections one of which carries the air valve and a screw sleeve connecting said valve stem sections, an operating shaft having a crank and intermediate means connecting said crank with said valve stems.

14. A water closet flushing apparatus comprising a water tank having a water inlet at its lower end, a water outlet above its lower end, an air passage arranged above said water outlet, an operating chamber communicating with said water outlet and air passage and provided below said water outlet with a discharge passage, said water outlet and air passage each comprising a bushing having an external screw thread and an internal valve seat and a nipple provided with an internal screw thread engaging said bushing and an internal guide bridge, water and air valves adapted to move toward and from the valve seats of said water outlet and air passages, respectively, and each provided with a valve stem which is guided at its rear end on the guide bridge of the respective nipple, a rock shaft journaled in said chamber and provided with a crank, and intermediate means connecting said crank with the front ends of said valve stems.
